UNITED STATES PATENT OFFICE

107,105

DESIGN FOR A LIGHTING TROUGH OR SIMILAR ARTICLE

Lemuel L. Stewart, Chicago, Ill., assignor to The Adlake Company, a corporation of Illinois

Application May 10, 1937, Serial No. 69,258

Term of patent 14 years

To all whom it may concern:

Be it known that I, Lemuel L. Stewart, a citizen of the United States of America, and a resident of Chicago, county of Cook, and State of Illinois, have invented a new, original, and ornamental Design for a Lighting Trough or Similar Article, of which the following is a specification, reference being had to the accompanying drawing, forming a part thereof, wherein

Fig. 1 is a perspective view of a trough or similar article showing my new design;

Figs. 2, 3 and 4 are fragmentary top plan, side elevational and bottom plan views, respectively; and

Fig. 5 is a section taken on the line 5—5 of Fig. 3.

I claim:

The ornamental design for a lighting trough or similar article, substantially as shown.

LEMUEL L. STEWART.
